UNITED STATES PATENT OFFICE

CHARLES H. JONES, OF PROVIDENCE, RHODE ISLAND, ASSIGNOR TO UNIVERSAL WINDING COMPANY, OF BOSTON, MASSACHUSETTS, A CORPORATION OF MASSACHUSETTS

WINDING MACHINE

Application filed August 9, 1928. Serial No. 298,518.

This invention relates to improvements in winding machines for winding silk, rayon and other delicate strand materials to produce "splicer" bobbins for use in knitting machines. The improvements are directed particularly to that type of machine in which the strand material is wound on a tapered or inclined chase to build a bobbin of generally cylindrical form having a conical or pointed nose from which the material delivers.

One object of the invention is to provide a winding machine having means for rotating the cop or bobbin and means for traversing the strand material on the tapered chase thereof, with the traversing-means or guiding-means adapted to follow the inclined surface on which the winding is performed without contact therewith.

Another object of the invention is to provide means for holding the guiding-means or thread-guide in close proximity to the surface on which the winding is performed, to insure an accurate disposition of the coils of winding, while avoiding contact of the guide therewith to prevent abrasion or chafing of the delicate strand material.

Another object of the invention is to provide a controlling-device for oscillating the thread-guide which is operated automatically from the reciprocating movement of the guide without the use of intervening means such as cranks, eccentrics or the like.

Another object of the invention is to provide a controlling-device for the traversing-means or thread-guide which may be applied to winding machines of standard types without material change in the construction or arrangement of the parts thereof.

Another object of the invention is to provide a controlling-device for the traversing-means which is adjustable to properly regulate the action of the thread-guide in winding cops and bobbins of different sizes and shapes.

Another object of the invention is to provide a device of the type specified which is simple in construction, efficient in action and proof against derangement and getting out of order.

Further objects of the improvement are set forth in the following specification which

describes a preferred form of construction of the invention, by way of example only, as illustrated by the accompanying drawings. In the drawings:

Fig. 1 is an end view of a winding machine showing the present improved controlling-means for the thread-guide as applied to use thereon;

Fig. 2 is a front elevation of the winding machine showing the general arrangement of the thread-guide controlling-device;

Fig. 3 is an enlarged detailed view of the winding mechanism, showing the winding-spindle, the thread-guide for traversing the yarn on the bobbin, the traverse-frame or mounting for the thread-guide, and the improved controlling-device which regulates the action of the thread-guide;

Fig. 4 is a detailed plan view of the thread-guide of the winding machine, showing the arrangement of the contact-wheel which contacts with the bobbin to feed the guide longitudinally of the axis thereof;

Fig. 5 is a perspective view of the rockable track or rail which oscillates the thread-guide to cause it to follow the inclined or conical face on which the winding is performed while holding the delivery point of the guide away from the surface of the winding;

Fig. 6 is a fragmentary perspective view showing a modified form of the track or rail as provided with adjustable means for regulating its oscillating movement; and

Fig. 7 is a perspective view of the element which acts to rock the track to oscillate the thread-guide.

In the present drawings the invention is illustrated as applied to use on a winding machine of well-known type comprising the main elements of a rotating winding-spindle, a reciprocable thread-guide, and means for reciprocating the thread-guide to adapt it to traverse the strand material on the cop or bobbin. In other cases, however, the machine may comprise means for longitudinally reciprocating the winding-spindle instead of the thread-guide, and still other forms of construction of the essential elements of the winding-mechanism may be employed which would fall within the spirit and scope of the

present invention. In the present type of machine the thread-guide is adapted to oscillate on its axis of reciprocation, whereby it is caused to follow the tapered surface of the winding, and means are provided for feeding the guide longitudinally of the bobbin to progressively advance the layers of winding from base to tip of the bobbin. In other types of machines, however, the advance or stepping forward of the layers of winding may be accomplished by moving the winding-spindle in an axial direction with respect to the thread-guide.

In Figs. 1 and 2 of the present drawings, 2 designates a box-like frame on which the various elements of the winding-mechanism are mounted, and 3 is the rotatable winding-spindle shown as journaled in suitable bearings 4 at the top of the frame. A cam-shaft 6, arranged below in parallel relation to the winding-spindle 3, is journaled in bearings 5 on the sides of the frame 2, and carried thereon to be driven thereby is a helical traverse-cam 7. The winding-spindle 3 and cam-shaft 6 may be connected to be rotated, one from the other, through the use of pulleys, gears or the like, not herein shown, the machine being driven from a suitable source of power such as a motor or counter-shaft, not shown.

The winding-spindle 3 extends beyond its bearing at the side of the frame 2 and is provided with a suitable mandrel or cop-holder for supporting the bobbin-receiver or tube C on which the winding is to be performed. As herein shown the winding-mandrel or cop-holder 8 is of generally cylindrical form, being provided at its inner end with an enlarged frusto-conical boss 9 for receiving the hollow tapered butt c' of the paper bobbin-receiver or tube C. Any suitable means may be employed for holding the bobbin-receiver or tube C on the mandrel 8, this device not being herein shown or described as it forms no part of the present invention.

Supported from the cam-shaft 6 of the machine is a traverse-frame 10, on which is slidably mounted the traversing thread-guide 25 to adapt it to be reciprocated longitudinally of the winding-spindle 3. The traverse-frame 10 is constructed with a horizontal cross-bar or member 11 having opposite depending arms 12 and 13 formed with hubs 14 and 15. The hubs 14 and 15 are bored to receive bushings 16, held fixedly in the bearings 5 on the frame 2, and in which the cam-shaft 6 is journaled to rotate.

A longitudinally-extending groove 17 in the cross-member 11 of the traverse-frame 10 provides a horizontal trackway for a slideable bar or rod 18. One end of the rod 18 is connected to a cross-head or slide 19 which carries a stud or roller 20 engaging in the helical groove 21 of the cam 7. It will be noted by reference to Fig. 2 that the cam 7 is secured fast on the cam-shaft 6 by means

of a key 22 and the rotation of the shaft turns the cam to reciprocate the slide 19 and rod 18.

The opposite or forward end of the rod 18 carries an upright arm 23 connected to a parallel sliding rod 24, see Figs. 2 and 3, which constitutes the traverse-bar for reciprocating the thread-guide 25. As shown in the present drawings, the traverse-bar 24 is mounted to slide in bearings 26 and 27 formed on a supplemental frame 28 attached to an overhanging portion 29 of the main traverse-frame 10. Referring particularly to Figs. 2 and 3, the supplemental frame 28 is constructed with a rail or bar 30 clamped to an upstanding flange 31 on the overhanging portion 29 of the traverse-frame 10 by means of screws 32. The lower edge of the rail 30 overhangs the groove 17 in the cross-bar 11 and portion 29 of the traverse-frame 10 and is formed with an arcuate bearing face abutting the side of the rod 18 to hold the latter in place in the groove, see Fig. 3.

The traverse-frame 10, as before stated, is swiveled to swing on the axis of the cam-shaft 6, being thus mounted to adapt it for adjustment to set the traverse-bar 24 in proper spaced relation with respect to the axis of the winding-spindle 3, this adjustment being altered for winding bobbins of different diameter as hereinafter more fully explained. The traverse-frame 10 is normally held in fixed position by means of a detent lock shown in detail in Fig. 3. Referring to Fig. 2, a horizontal rod 33 extends through the side of the forward arm 12 of the traverse-frame 10, being further supported in a lug 34 at the end of the traverse-frame extension 29 and also in a lug 35 at the outer end of the supplementary frame 28.

The rod 33 is rockable in its bearings and carries a weighted detent-arm 36 secured in place thereon by means of a set-screw 37, see Fig. 3. The detent-arm 36 is formed on its inner side with a detent-lug or latch 38 which is engageable with a shoulder 39 on a fixed locking-member 40. The locking-member 40 is of arcuate form and provided with a slot 41 for receiving a bolt 42 by means of which the lock is fixedly clamped to the side of the frame 2. The locking-member 40 may be adjusted in position by loosening its bolt 42 whereby to properly locate the detent-shoulder 39 to hold the traverse-frame in fixed position with the traverse-bar 24 in predetermined relation to the winding-spindle 3.

The lug or latch 38 on the detent-arm 36 may be released from the detent-shoulder 39 by rocking the arm 36 upwardly through the means of the rod 33; this release of the detents being effected automatically when the winding of a bobbin is completed whereby to permit the traverse-frame 10 to swing away from the winding-spindle so that the bobbin may be more readily doffed therefrom. For this purpose the rod 33 carries

an upright lever 43, see Fig. 2, which has an inclined upper end 44 adapted to be engaged by the thread-guide 25 when the guide has been fed out to the end of the bobbin. The lever 43 may be adjusted longitudinally of the rod 33 to cause it to be engaged by the thread-guide 25 when the latter has been fed outwardly along the traverse-bar 24 to a predetermined extent in winding a bobbin of 10 the required length.

As before stated, the traverse-bar 24 is reciprocated on the supplemental frame 28 and, as shown in Fig. 2, the bar slides in bushings 47 driven into the bearings 26 and 15 27 on the frame. At the outer end of the frame 28 the bearing 26 is extended to provide a guard for the end of the bar as it slides to its extreme of traverse.

Referring to Fig. 3, the arm 23 which connects the traverse-bar 24 with the lower rod 18 has an offset or bent portion 48 fixedly held in a slot in the rod. At its upper end the arm 23 is bent around at 54 to encompass the traverse-bar 24 and is clamped 25 thereto by means of a screw 49. The screw 49 serves a further purpose in providing means for attaching an element of the guide-controlling device to the arm 23, as will be later explained.

Referring to Fig. 4, the traverse-bar is of usual construction, being provided with screw-threads 50 cut into its side in eccentric relation to its axis. The screw-threads 50 are adapted to engage corresponding 35 threads on the interior of a cylindrical nut or sleeve 51 which is rotated to advance or feed the thread-guide 25 longitudinally of the traverse-bar 24. The sleeve or nut 51 extends between and is straddled by the legs 40 52 and 53 of a bifurcated thread-guide holder 55, the ends of the legs being provided with bearings 56 and 57 swiveled on the bar 24 to adapt the holder to oscillate about the axis thereof. The thread-guide proper may be 45 constituted by a grooved, porcelain roll 58 secured to the outer end of the holder 55 by means of a screw or stud 59.

On the sleeve or nut 51 is a flanged disk 60 to the side of which is attached a contact-wheel 61. The contact-wheel 61 has a flanged peripheral rim adapted to make contact with the surface of the winding on the bobbin whereby to turn the nut 51 on the bar 24. The periphery of the contact-wheel 55 61 makes contact with the base of the conical chase of the winding at each rearward stroke of the thread-guide 25 and is thereby rotated to a slight extent to turn the nut 51 to feed the guide progressively outward along the 60 traverse-bar 24. The bore of the nut 51 is of larger diameter than the bar 24 so that it may be moved laterally to disengage its threads from the threads on the bar when it is required to release the nut to adjust the thread-guide 25 to first position at the start of the

winding. The nut 51 is normally held in eccentric relation with respect to the axis of the bar 24, to maintain engagement between the threads on the bar and nut, by means of a spring 62. The spring 62 has a 70 coiled portion 63 with an arm 64 reaching outwardly therefrom and bearing against the rim of the disk 60 on the nut 51. The construction and arrangement of the parts last described is substantially the same as generally employed on bobbins and cop-winding machines in which the thread-guide is advanced longitudinally of the winding-spindle to deposit the yarn in forwardly-stepped 75 courses laid on an inclined or conical chase.

As the thread-guide 25 is reciprocated longitudinally of the winding-spindle 3 the thread-guide holder or arm 55 is oscillated about the axis of the traverse-bar 24 to adapt the strand-feeding or delivering portion of 80 the guide to follow up and down the inclined chase of the bobbin being wound. In previously used bobbin-winding machines of the present type the thread-guide is designed to bear against the surface of the winding to 85 direct its course up and down the inclined chase of the bobbin. It has been found, however, that in winding certain materials, such as silk, rayon and other delicate yarns, the contact of the guide with the surface of the 90 bobbin causes a chafing and abrasive action which has a deleterious effect on the material. That is to say, the rubbing action of the guide on the bobbin chafes and roughens the material and spoils the finish of the 95 yarn. It is therefore a prime object of the present improvement, to eliminate this chafing or abrasive action of the guide on the material, and to this end means are provided for controlling the movement of the thread-guide to 100 cause it to follow the chase of the bobbin without contact thereon. In the present form of construction of the invention the means for controlling the movement of the 105 guide consists of a device for oscillating the thread-guide holder 55 on the traverse-bar 24 during the reciprocatory motion of the 110 guide in a certain predetermined path. The guide-controlling device is operated from the traversing-means synchronously therewith. 115 and a preferred form of construction of the mechanism employed for this purpose will next be described.

Referring to Figs. 1, 2 and 3, the thread-guide controlling means comprise a rockable 120 guiding-track 67, preferably constructed in the form of a sheet-metal yoke or bifurcated frame as illustrated in perspective view in Fig. 5. The frame 65 is constituted by a longitudinal bar 66, preferably of angle-iron 125 shape in cross section to provide an overhanging rail or track 67. Laterally-extending arms 68 at the ends of the rail 66 terminate in ears 69 provided with holes 70 whereby the frame 65 may be rockably mounted on the 130

ends of the bushings 47, before referred to as held in the bearings 26 and 27 on the supplemental traverse-frame 28.

At the inner end of the frame 65 the rail 67 is extended downwardly in an arcuately-shaped triangular portion 74, see Figs. 3 and 4, disposed in concentric relation with respect to the axis of the traverse-rod 24 on which the frame is swiveled. The depending portion 74 is formed with a cam-slot 75 inclined downwardly from the horizontal and adapted to receive a sliding stud or pin 76 projecting forwardly from an elbow-shaped arm 77 carried by the traverse-bar 24. As herein shown the arm 77, illustrated in detail in Fig. 7, is provided with a downwardly bent forward end 78, through which the pin 76 is riveted; and its rearward end is bent over to adapt it to overlie the top and side of the traverse-arm 23 which, as before explained, is clamped around the traverse-rod 24. The depending rearward portion 79 of the arm 77 is formed at its lower end with a right-angled lip 80 projecting forwardly toward the traverse-arm 23 and slotted at 81 to adapt it to straddle the sides thereof. In the portion 79 of the arm 77 is a hole 82 for receiving the screw 49 which clamps the bent end 54 of the arm 23 to the rod 24. Lugs 73 project forwardly from the rearward portion 79 of the arm 77 to bear against the back of the arm 23 and when the screw 49 is screwed into place its head will bind against this part of the arm 77 to clamp it securely to the arm 23, the slotted lip 80 preventing the arm 77 from turning or skewing out of position.

It will now be apparent that when the traverse-bar 24 is reciprocated in the guide-way of the frame 10 with the arm 77 moving therewith, the pin 76 will be carried back and forth longitudinally of the cam-slot 75 in the frame 65. As the slot 75 is inclined from the path of travel of the pin 76 the sliding movement of the latter in the slot will have the effect to rock the frame 65 on the axis of the traverse-bar 24. The alternate rising and falling motion of the rail 67 on the frame 65 is caused to oscillate the thread-guide 25 to carry its delivery point toward and away from the axis of the winding-spindle 3. This action is accomplished through the means of a sliding connection between the guide-holder or arm 55 of the guide 25 and the rail or track 67 of the frame 65. For this purpose the guide-holder 55 is provided with a finger 83 projecting rearwardly from its leg 53, see Figs. 2, 3 and 4, and bent around to form a shoe 84 which is adapted to hook around and straddle the rail 67 on the frame 65.

It will be understood that in the form of construction of the frame 65 as shown in Fig. 5 the cam-slot 75 is inclined to the horizontal path of the pin 76 at a predetermined angle to cause it to impart to the frame 65 the proper extent of rocking motion to carry the

thread-guide 25 from a position adjacent the outer circumference of the bobbin being wound, as illustrated in full lines in Fig. 3, to a position contiguous to the surface of the cylindrical barrel *c* of the bobbin-carrier, as indicated by the dotted lines in this view. To adapt the winding machine for winding bobbins of different proportions, however, it is desirable that the controlling-device be provided with adjustable means for altering the extent of oscillation of the thread-guide, and for this purpose a modified form of the frame may be employed as illustrated in Fig. 6 of the drawings. As here shown the cam-slot or trackway 85 for the pin 76 is formed in a separate member or arm 86 which is pivotally connected to the end of the rockable frame 87 by suitable means such as the screw 88. At its opposite end the slotted member 86 is provided with an arcuate slot 89 through which extends a screw 90 screwed into an ear 91 depending from the rail 92 of the frame 87. By loosening the screw 90 the outer end of the member 86 may be swung up or down on its pivot to adjust the inclination of the cam-slot 85 to regulate the extent of throw of the thread-guide 25 in accordance with requirements in winding bobbins of varying sizes or proportions. The frame 87 may be substituted for the frame 65 without other alteration in the construction of the machine and its method of functioning to control the oscillatory movement of the thread-guide is the same as previously explained.

The method of operation of the complete machine is as follows: The paper tube or other form of bobbin-receiver *C* is placed on the mandrel 8 of the winding-spindle 3 and the end of the yarn or other strand *y* leading from the source of supply, not herein shown, is attached to the tube in any suitable manner. The strand *y* may lead from a supply arranged below or, as shown in the present drawings, it may draw downwardly from a swift, spool or the like placed above the machine in any convenient location. The strand *y* is carried around the porcelain roll 58 as it draws to the carrier *C* on the winding mandrel whereby it will feed from the guide directly to the surface on which the winding is to be performed.

Before starting the machine the traverse-frame 10 is set in the position illustrated in Figs. 1 and 3 and locked in place with the detent-lug 38 on the latch 36 engaged with the shoulder 39 on the member 40. The thread-guide 25 is then adjusted to starting position by sliding it back on the traverse-bar 24 until the center of its roll 58 aligns substantially with the rearward end of the base *c* of the bobbin-carrier *C*, the adjustment of the guide to this position being accomplished by releasing the nut 51 from the threads 50 on the bar 24 in the manner as previously explained. The adjustment of the thread-

guide 25 to starting position brings the contact-wheel 61 opposite the base of the conical portion c' of the bobbin-receiver C to adapt it to contact with the first layers of yarn 5 deposited thereon whereby, during the winding, the rotation of the contact-wheel will act to progressively advance the layers of winding outwardly along the bobbin.

With the parts of the machine set in the 10 position as above described the roll 58 of the thread-guide 25 will assume a position just clear of the outer circumference of the inclined portion c' of the bobbin-carrier C as indicated by full lines in Fig. 3. The machine is started to operate through the shifting of a clutch or other instrumentalities, not herein shown, which are controlled through the manipulation of a starting-lever or handle 95 illustrated in Figs. 1 and 2 of the 15 drawings. As power is applied to the machine in this manner the winding-spindle 3 is driven to rotate the bobbin-receiver C, and the cam 7 is rotated therefrom to reciprocate the rod 18 in the guideway 17 of the traverse-frame 10. The rod 18 imparts reciprocation to the traverse-bar 24 through the medium of the arm 23 connecting these parts. As the traverse-bar 24 is reciprocated the thread-guide 25 carried thereby is traversed back 20 and forth longitudinally of the winding-spindle 3 with an extent of traverse defined by the throw of the cam 7 which is in proportion to the length of the chase to be wound on the tapered butt c' of the bobbin-carrier 25 C. Initially, the thread-guide 25 will be traversed between the base end of the conical butt c' and the point where its smaller end joins the cylindrical barrel c . The guide 25 is thus caused to lay the yarn y in helical 30 coils deposited upon the conical surface of the butt c' of the carrier in the usual manner as practiced in winding bobbins of the present type.

As before stated it is desirable that the 45 delivering point of the guide, that is the point from which the strand feeds to the bobbin, be maintained in close relation with respect to the surface on which the winding is being performed to insure the proper disposition 50 of the coils thereon. In previously used machines of the present type it has been the practice to allow the guide to contact with the surface of the winding to direct its course up and down the inclined chase of the bobbin, 55 means being usually provided for holding the guide against the bobbin under tension. In the present invention a prime object of the improvement is to prevent the contact of the thread-guide with the surface of the winding 60 while adapting it to follow the incline of the tapered chase on which the winding is being performed.

To provide for this control or regulation 65 of the oscillating movement of the thread-guide toward and away from the axis of the

winding-spindle the present improved controlling-device functions as follows: With the thread-guide 25 at the rearward end of its throw or traverse the pin 76 on the arm 77 will be positioned at the right-hand end 70 of the cam-slot 75 in the frame 65 as illustrated in Fig. 2 of the drawings. Now, as the traverse-bar 24 is reciprocated from the cam 7 through the medium of the sliding rod 18 it will carry the thread-guide 25 outwardly 75 or to the left as viewed in Fig. 2. As the guide 25 is moved in this direction the pin 76 on the arm 77 which, as before explained, is fixedly attached to the arm 23 extending between the rods 18 and 24, will be slid to the outer end of the cam-slot 75. It will be understood that the pin 76 is held by the arm 77 to move in a horizontal course parallel with the axis of the traverse-rod 24. Consequently, as the pin 76 rides along the cam groove 75 it will act to rock the frame 65 upwardly to correspondingly lift the guide-rail 67. This raising of the guide-rail or track 67 of the frame 65 acts through the finger 83 on the thread-guide holder 55 to rock the latter on the axis of the rod 24 whereby to carry the guide-roll 58 inwardly from the position shown by full lines in Fig. 3 to the position indicated by dotted lines in this view. In other words, the rocking of the frame 65 will oscillate the thread-guide 25 to cause the guide-roll 58 to follow down the inclined surface of the winding, but the relation between the parts are such as to prevent the roll from contacting with the winding. As the guide 25 is carried back in the opposite direction the pin 76 slides towards the inner 80 end of the cam-slot 75 to rock the frame 65 85 downwardly again into first position. During this return throw of the guide 25 the frame 65 is caused to oscillate the guide-holder 55 to move the roll 58 up the incline of the chase while directing its course to prevent it from contacting with the surface of the winding. In this manner the oscillating or 90 and fro motion of the thread-guide is effected synchronously with its longitudinal traversing motion.

As the strand material is deposited on the butt c' on the bobbin-carrier C it will build up in layers of crossing turns or coils, and eventually the contact-wheel 61 will be engaged by the winding at the inner end of the stroke of the guide 25. During this brief engagement the contact-wheel 61 is rotated 105 to a slight extent to turn the nut 51 which, through its engagement with the screw-threads 50 on the rod 24, is caused to feed the thread-guide outwardly on the bar. This 110 action takes place at the end of each rearward stroke of the thread-guide 25 so that the overlying courses of winding are advanced progressively along the receiver C to 115 build the bobbin in the usual manner whereby it is formed with a cylindrical body and 120

a tapered or conical nose-end as indicated by the dot-and-dash lines in Fig. 2. It will be understood that as the thread-guide 25 feeds outwardly on the traverse-rod 24 the bent portion or shoe 84 on the finger 83 slides along the track or rail 67 to maintain the connection between the rockable frame 65 and the thread-guide 25.

After the thread-guide 25 has been fed outwardly on the traverse-bar 24 to a sufficient extent to complete the bobbin to the required length, finally, at the outward traverse of the guide, the leg 52 of the guide-holder 55 makes contact with the inclined end of the arm or lever 48 to rock the rod 83. The rocking of the rod 83 releases the detent-latch 36 from the locking member 40 and thus the traverse-frame 10 is unlocked to allow it to swing back under the action of gravity to remove the contact-wheel 61 from further contact with the winding. At this juncture suitable instrumentalities, not herein shown, are brought into action to disconnect the drive of the machine to arrest the winding operation, whereupon the completed bobbin may be doffed from the mandrel 8 and a new tube or receiver placed thereon.

I am aware that it has before been proposed to oscillate the thread-guide of a bobbin-winding machine to direct its course in parallel relation with respect to the inclined chase of the bobbin while holding it from contacting with the surface of the winding. Such a form of construction is shown and described in the pending application of J. A. Anderson, Serial No. 281,571, filed May 29, 1928, now Patent No. 1,819,695, Aug. 18, 1931, but in the machine of this application the oscillation of the thread-guide is effected through the use of a crank or eccentric rotated from a going part of the machine. In the present invention the use of such a crank-motion or eccentric for oscillating the thread-guide is dispensed with, whereby to simplify the construction of the controlling-device and further to render it more positive and direct in operation. In the present invention the longitudinal traversing movement of the thread-guide is employed to effect and control the actuation of the frame which oscillates the thread-guide, and through this arrangement a number of elements are eliminated, the mechanism simplified and rendered more compact, and other advantages secured which will be readily apparent to those skilled in the art.

In accordance with one form of construction of the invention as herein shown and described the oscillating device for the thread-guide is made adjustable to regulate the extent of movement of the thread-guide and to control its range of action for bobbins of different proportions or sizes. This adjusting-means is extremely simple in structure, convenient to set and proof against derangement and getting out of order. The

mechanism of the whole device, in fact, is reduced to the utmost simplicity while being improved in efficiency of operation.

It is further to be observed that the cam-track on the rockable frame and its follower actuated from the reciprocating motion of the thread-guide are susceptible of a change in their relation or, in other words, a reversal of the parts without affecting their method of operation for the purpose explained.

While I have herein described and illustrated the improvement as applied to use with a certain type of winding machine, and as embodied in a preferred form of construction, it is to be understood that various modifications may be made to adapt the device to other forms of winding machines, and also in the structure and arrangement of its parts, without departing from the spirit or scope of the invention. Therefore, without limiting myself in this respect, I claim:

1. In a winding machine for winding a bobbin having the yarn laid in inclined chases, the combination of means for rotating the bobbin, guiding-means for traversing strand material to deposit it on the inclined chase of the bobbin, means for progressively advancing the guiding-means along the axis of the bobbin, and an oscillating-member actuated from the relative movement between the bobbin and the guiding-means to rock the guiding-means to maintain the latter in adjacent relation to the inclined surface on which the winding is performed without contact therewith.

2. In a winding machine, the combination of a winding-spindle, a thread-guide for guiding strand material to wind a bobbin on the spindle, means for effecting a relative longitudinal traverse between the winding-spindle and thread-guide, means for causing a relative advance of the thread-guide longitudinally of the winding-spindle, and an oscillating-member actuated from the traversing motion to rock the thread-guide to maintain it in proximity with the surface on which the winding is performed while preventing it from contacting therewith.

3. In a winding machine, the combination of a winding-spindle, a thread-guide for feeding strand material to the spindle to wind a cop or bobbin thereon, means for effecting a relative traverse between the winding-spindle and thread-guide, means for causing a relative advance of the thread-guide longitudinally of the winding-spindle, and an oscillating-member actuated from the traversing motion between the spindle and guide and operating on the thread-guide to cause it to move toward and away from the winding-spindle to follow the taper of the conical chase of the bobbin without contact therewith.

4. In a winding machine, the combination of a winding-spindle, a thread-guide for

feeding strand material to the winding-spindle to wind a cop or bobbin thereon, means for traversing the thread-guide longitudinally of the winding-spindle, means for progressively advancing the thread-guide along the winding spindle, and an oscillating-member actuated by the traversing motion of the thread-guide and acting thereon to direct the guide in a path inclined to the axis of the 10 spindle to cause it to follow the inclined chase of the bobbin without contact therewith.

5. In a winding machine, the combination of a winding-spindle, a thread-guide for traversing strand material longitudinally of the 15 spindle to wind a cop or bobbin, means to feed the thread-guide along the winding-spindle to build the bobbin in progressively advanced courses, an oscillating-member for rocking the thread-guide toward and away 20 from the axis of the winding-spindle during its traverse with respect thereto to cause it to follow the inclined chase of the bobbin, and means actuated by the traversing motion of the thread-guide to oscillate said member.

6. In a winding machine, the combination of a winding-spindle, a reciprocating traverse-means, a thread-guide connected to be reciprocated from said traverse-means, means 30 to progressively feed the thread-guide along the winding-spindle, and means oscillated from the reciprocating motion of the traverse-means and acting on the thread-guide to rock the latter to cause it to follow the inclined 35 chase of the bobbin without contact therewith.

7. In a winding machine, the combination of a winding-spindle, a reciprocating traverse-bar, a thread-guide swiveled to rock on the 40 traverse-bar, means to reciprocate the traverse-bar to cause the guide to traverse strand material to wind a bobbin on the spindle, and a rockable member actuated from the reciprocating motion of the traverse-bar to oscillate the thread-guide to cause it to follow the inclined chase of the bobbin 45 without contact therewith.

8. In a winding machine, the combination of a winding-spindle, an oscillatable and 50 reciprocable thread-guide for traversing strand material on the winding-spindle to deposit it in inclined courses, reciprocating means for traversing the thread-guide, a rockable member connected with the thread-guide, and means actuated from the longitudinal movement of the reciprocating-means to rock said member to oscillate the thread-guide toward and away from the axis of the winding-spindle to cause it to follow the inclined 55 chase of the bobbin without contact therewith.

9. In a winding machine, the combination of a winding-spindle, a traverse-bar, a 60 thread-guide connected thereto, means to reciprocate the traverse-bar to cause the

thread-guide to traverse strand material to wind a bobbin on the spindle, a rockable track, means connected to the thread-guide and slidable on the track, and means actuated by the motion of the traverse-bar to rock the track to oscillate the thread-guide to cause it to follow the inclined chase of the bobbin. 70

10. In a winding machine, the combination of a winding-spindle, a reciprocable traverse-bar, means to reciprocate the traverse-bar, a thread-guide swiveled on the traverse-bar and adapted to be progressively fed therewith, a track swiveled to rock on the axis of the traverse-bar, means on the thread-guide 75 slidably engaging the track, and means actuated from reciprocation of the traverse-bar to rock the track to oscillate the thread-guide to cause it to follow the inclined chase of the bobbin. 80

11. In a winding machine, the combination of a winding-spindle, a thread-guide for feeding strand material to the winding-spindle to wind a cop or bobbin thereon, means for effecting a relative traverse between the winding-spindle and thread-guide, means for causing a relative advance of the thread-guide longitudinally of the winding-spindle, an oscillating-member connected to the thread-guide and acting to rock the latter to cause it to follow the inclined chase of the bobbin during its traverse, an inclined cam-track on the oscillating-member, and means engaging the cam to oscillate said member during each traverse of the thread-guide. 90

12. In a winding machine, the combination of a winding-spindle, a thread-guide for traversing strand material to wind a cop or bobbin on the spindle, means for reciprocating the thread-guide, means for progressively advancing the thread-guide along the winding-spindle, an oscillating-member connected to the thread-guide and acting thereon to cause it to follow the inclined chase of the bobbin during its traverse, and a cam for actuating the oscillating-member at each 100 reciprocation of the guide. 105

13. In a winding machine, the combination of a winding-spindle, a thread-guide for traversing strand material to wind a cop or bobbin on the spindle, means for reciprocating the thread-guide, means for progressively advancing the thread-guide along the winding-spindle, an oscillating cam-track, means connecting the cam-track with the thread-guide, and means movable with the reciprocating-means and engaging the cam-track to oscillate the latter to carry the thread-guide toward and away from the axis of the winding-spindle during its reciprocation with respect thereto. 115 120

14. In a winding machine, the combination of a winding-spindle, an oscillable thread-guide arranged to move toward and away from the winding-spindle, means for reciprocating the thread-guide, an inclined cam- 130

track, means engaging the cam-track to rock the latter during the reciprocation of the thread-guide, and means connecting the cam-track to oscillate the guide to cause it to follow the inclined chase of the bobbin without contact therewith.

15. In a winding-machine, the combination of a winding-spindle, a reciprocable thread-guide arranged to oscillate toward and away from the axis of the winding-spindle, means to reciprocate the thread-guide, means to progressively feed the thread-guide along the winding-spindle, a rockable member connected to oscillate the thread-guide, a cam, and means actuated from the reciprocating means to follow the cam to rock the member.

16. In a winding machine, the combination of a winding-spindle, a reciprocable thread-guide arranged to oscillate toward and away from the axis of the winding-spindle, a rockable frame connected to oscillate the thread-guide, an inclined cam-track on the frame, and means reciprocated with the guide and engaging the cam-track to rock the frame to oscillate the thread-guide.

17. In a winding machine, the combination of a winding-spindle, a reciprocable thread-guide arranged to oscillate toward and away from the winding-spindle, means to reciprocate the thread-guide, means to progressively feed the thread-guide along the winding-spindle during its reciprocation, a rockable cam, means engaging the cam to rock the latter, means connecting the cam with the thread-guide to oscillate the latter at each reciprocation thereof, and means for adjusting the cam to regulate the extent of oscillating motion of the thread-guide.

18. In a winding machine, the combination of a winding-spindle, a reciprocating traverse-bar, means for reciprocating the traverse-bar, a thread-guide reciprocated from the traverse-bar and arranged to oscillate toward and away from the axis of the winding-spindle, a rockable member connected to oscillate the thread-guide, an inclined cam-track on said member, and a follower reciprocable with the traverse-bar and adapted to travel on the cam-track to rock the oscillating member.

In testimony whereof I hereunto affix my signature.

CHARLES H. JONES.
